David L. Bartlett Design for Stove

Des. 278

David L. Bartlett of Baltimore Md.
Letters Patent No. 248. Dated April 9, 1850.

The Schedule referred to in these Letters Patent and making part of the same.

To all whom it may concern:

Be it known that I, David L. Bartlett of the City & County of Baltimore, State of Maryland, have invented or produced a new and original Design for Stoves: and I do hereby declare the following, a full and exact description of the same, reference being had to the accompanying drawings, which are a perspective view of the Stove with a front view of one of its legs.

Around the top is an Ogee moulding ornamented with interlaced trefoils. (A. A) The Frieze ornamented with Quarter foils, (B. B. B. B.) having triangular sinks (C. C. C. C.) at their angles between them. The body has two rows of Gothic arches, the upper row (D. D.) having more than the lower one. The lower, (E. E.) being larger than the upper one.

At the top and between the lower arches (at their angles) is a Gothic triangular rosette (F. F. F.).

At the top and between the upper arches are triangular sinks (G. G. G.). In front and rear of the stove is a tall arch (H. H.) extending nearly from bottom of the stove to the Frieze, and near the corners of the stove.

Also one tall arch (I) directly at the corners of the stove. The short arches in the upper row have quarterfoils (K. K.) at top.

The panels of all the arches except the corner ones, are enriched with diamond lines resembling windows, each diamond having an indent (L. L. L.) resembling a star.

225.

Around the bottom is a Bead decorated with Gothic scroll work. (M. M. M) (o) is a view of Leg.

I claim the foregoing described and illustrated Design for Stoves.

Witnesses.
